UNITED STATES PATENT OFFICE.

EDWIN F. HULBERT, OF KENOSHA, WISCONSIN, ASSIGNOR TO NATIONAL OYSTER CARRIER CO., OF KENOSHA, WISCONSIN.

CAN-LOCK.

No. 910,199.

Specification of Letters Patent.

Patented Jan. 19, 1909.

Application filed October 24, 1907. Serial No. 399,068.

To all whom it may concern:

Be it known that I, EDWIN F. HULBERT, citizen of the United States, residing at Kenosha, in the county of Kenosha and State 5 of Wisconsin, have invented certain new and useful Improvements in Can-Locks, of which the following is a specification.

This invention contemplates certain new and useful improvements in shipping and 10 storing vessels, and relates particularly to an improved lock for the closure of a shipping can for oysters or other commodities.

The invention has for its object a simple, durable and efficient construction of can 15 lock in the nature of a sectional hasp that is designed to tightly bind the closure to the body of the can so as to maintain an efficient seal or joint and to receive a sealing strip or the like so that the closure can not be re- 20 moved or swung open without breaking the seal.

With these and other objects in view as will more fully appear as the description 25 proceeds, the invention consists in certain constructions, arrangements and combinations of the parts that I shall hereinafter fully describe and claim.

For a full understanding of the invention, reference is to be had to the following 30 description and accompanying drawings, in which:

Figure 1 is a perspective view of a shipping can embodying the improvements of my invention; Fig. 2 is an enlarged longitudinal sectional view through the locking devices, illustrating the same in engaged position; and, Fig. 3 is a similar view of the devices partly disengaged.

Corresponding and like parts are referred 40 to in the following description and indicated in all the views of the drawings by the same reference characters.

Referring to the drawing, the numeral 1 designates a shipping or storing can which 45 is provided in its top with an opening 2 around which is formed a marginal flange 3 preferably curled in the form of an annular bead, as shown and forming part of a short upstanding collar 4 formed on or secured to 50 the top of the can.

The closure 5 for the opening 2 is preferably dished, as shown, and is adapted to accurately fit in the opening and is formed at its upper edge with a marginal flange 5^a

corresponding to and adapted to fit upon the 55 flange 3. The closure 5 in the present instance is hinged to the top of the can by means of a metal strip 6 and an arched bar 7, as shown.

The closure 5 is provided at its free end 60 with a staple 8 to which the sectional hasp forming part of my invention is hingedly connected. This hasp comprises two sections 9 and 10 that are hinged together at one end as indicated at 11, the outermost section being 65 provided at its extremity with a hook 12, designed to embrace and tightly clamp together the two flanges 3 and 5^a when the closure is in place in the opening 2 and when one section of the hasp is folded down upon 70 the other and the entire hasp swung down into or on top of the closure.

The sections 9 and 10 of the hasp are formed near their joint with registering 75 slots 13 and 14, designed to receive a staple 15 secured to the closure 5 and constituting the keeper for the hasp, and the outer section 10 is also formed with another slot 16 designed to receive the staple 17 secured to 80 the outer section 9.

18 designates a seal which is adapted to be inserted through the staples 17 and 15 to 85 secure the hooked section of the hasp down upon the other section and both sections to the closure.

From the foregoing description in connection with the accompanying drawing, it is believed that the operation of my improved can closure and lock and the construction thereof are obvious. When the 90 two parts that are to be locked together, namely, the can body or top and the closure therefor are closed one upon the other, the entire hasp is first swung up substantially to the position illustrated in Fig. 3 and the 95 outer or hinged section 10 of the hasp is swung in one direction so that its hook engages and embraces the two flanges 5^a and 3. The other section or main portion 9 of the hasp is then swung or pressed downwardly 100 in the opposite direction around its point of connection with the closure, such point of connection being located between the point where the hook 12 engages with the flanges and the keeper formed by the staple 15. 105 This action securely joins the hook into engagement with the two parts to be secured together, that is the can top and the closure

therefor, and, after the hasp has been swung downwardly so that the staple or keeper 15 projects through both sections of the hasp, the seal 18 is applied. It will thus be seen

5 that the closure is effectually locked with a tight sealing action, and that it cannot be opened until the seal 18 has been broken.

Having thus described the invention, what is claimed as new is:

10 1. The combination of parts to be locked together, of a keeper secured to one of said parts, and a hasp constructed in sections, namely a section movably connected to such part and arranged to swing in one direction 15 into engagement with said keeper and another section arranged to swing in the opposite direction into locking engagement with the other part.

2. The combination of parts to be locked together, of a hasp constructed in sections, namely a main section movably connected at one end to such part, and arranged to swing in one direction into engagement with said keeper and another section so connected to 25 the other end of the first named section as to swing in the opposite direction into engagement with the other part, the point of connection of the hasp and the first named part to which it is attached lying between 30 the keeper and the point of locking engagement of the said other section of the hasp with the said other part.

3. The combination of parts to be locked together, of a keeper secured to one of said parts, a hasp movably connected to such part and arranged to swing in one direction into engagement with said keeper and embodying a section arranged to swing in the opposite direction and formed at its free end with a 40 hook arranged for locking engagement with the other part, such other part being formed with a flange for such locking engagement.

4. The combination with parts to be locked together, of a keeper secured to one 45 of said parts, a hasp connected at one end to such part and arranged to swing in one direction into engagement with said keeper and embodying a section so connected to its other end as to swing in the opposite direction into locking engagement with the other 50 part, the point of connection of the hasp and the first named part to which it is attached lying between the keeper and the point of

locking engagement of the said section of the hasp with the other part, such section of 55 the hasp being also arranged for engagement with the keeper.

5. The combination with a vessel of the character described, formed with an opening and a closure for said opening, of a hasp secured to one of said parts and consisting of hinged sections adapted to lie one upon the other, the outermost section being formed with a hook arranged to engage the two parts to hold them together, said sections 65 being formed with registering slots, and a staple secured to one of said parts and adapted to project through said slots, whereby to receive a seal.

6. The combination with a vessel of the 70 character described, formed with an opening and a closure for said opening, of a hasp hinged to the closure and constructed in hinged sections adapted to lie one upon the other, the outermost section being formed 75 with a hook designed to secure the closure to the vessel, the other section being provided with a staple, and the hooked section being formed with a slot adapted to receive said staple, both of said sections being formed 80 with slots near their hinged connection, and the closure being provided with a staple adapted for reception in said last named slot.

7. The combination with a vessel of the 85 character described, formed with an opening, and a marginal flange arranged to fit said opening, a closure adapted to fit in said flange and formed with a corresponding flange, a hasp hinged to said closure and 90 constructed in hinged sections, the outermost one of which is formed with a hook adapted to take over the two flanges, said sections being formed with registering slots, a staple secured to the closure and designed 95 for reception in said slots, the hinged section being provided with a slot and the other section with a staple adapted to be received in said last named slot.

In testimony whereof I affix my signature 100 in presence of two witnesses.

EDWIN F. HULBERT. [L.S.]
